PULL FOR A SLIDE FASTENER

Alfred E. Carlile, 572 Chestnut St., Meadville, Pa.

Filed Sept. 11, 1961, Ser. No. 66,672

Term of patent 14 years

(Cl. D17—8)

Fig. 1.

Fig. 2.

Fig. 3.

Fig. 4.

FIG. 1 is a plan view of a pull for a slide fastener showing my new design;

FIG. 2 is a side view of the same;

FIG. 3 is a top end view of the same; and

FIG. 4 is a bottom end view of the same.

The broken line showing of a slider for a slide fastener is for illustrative purposes only.

I claim:

The ornamental design for a pull for a slide fastener, substantially as shown and described.
